UNITED STATES PATENT OFFICE.

JOHN J. DONLON, OF LYNN, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING UPON SOLES.

1,179,509.

Specification of Letters Patent. Patented Apr. 18, 1916.

Application filed August 28, 1913. Serial No. 787,147.

To all whom it may concern:

Be it known that I, JOHN J. DONLON, a citizen of the United States, residing at Lynn, in the county of Essex and State of Massachusetts, have invented certain new and useful Improvements in Machines for Operating upon Soles; and I do hereby declare the following to be a full, clear, and exact description of the invention, such as will enable others skilled in the art to which it appertains to make and use the same.

The present invention relates to a machine for operating upon soles after they have been incorporated in boots or shoes and more particularly to machines of this character which perform the operations of laying the channel flap and leveling the sole.

In the majority of shoes it is customary to form a channel in the marginal portion of the sole surface to receive the line of stitches securing the outsole to the lasted shoe. After the sole has been incorporated in the shoe and prior to the leveling or forming of the sole to its final shape it is necessary to lay and smooth out the flap covering this channel in order that the surface of the sole after leveling shall present a smooth unbroken appearance. In the manufacture of that class of shoes which are leveled by direct pressure it has been customary heretofore to perform the operation of laying the channel flap either upon a separate machine, or more commonly, by a manual operation after the shoe has been jacked upon the leveling machine. It will be obvious to those skilled in the art that both of these methods are more or less objectionable as the first involves a certain loss of time which must elapse between the two operations and in the second method the character of the work performed and the length of time necessary to lay the channel flap depend wholly upon the care and skill of the operator.

One object of the present invention is to provide a machine which shall perform the two separate operations of laying the channel flap and leveling the sole by direct pressure without requiring any manual interference upon the part of the operator.

With this object in view, one feature of the invention consists in the combination of a shoe supporting member, a pressing member, means for relatively actuating the members to level the sole by direct pressure, and

means for laying the channel flap of a shoe 55 sole.

Another feature of the invention contemplates the provision in a machine of the class described, having a pressing form, a shoe supporting jack, and means for moving the jack inwardly and upwardly from a position of presentation to a position of pressure, of means actuated upon the inward movement of the jack to lay the channel flap 65 of the sole.

A further feature of the invention consists in the provision of mechanism for causing the flap laying device to operatively engage with the sole during the movement of the jack in one direction and for retaining the 70 flap laying device out of operative engagement with the sole during the movement of the jack in the opposite direction. In the simplest and most efficient form of the invention which has yet been devised the flap laying device engages with the sole during the movement of the jack from a position of presentation to a position of pressure and is removed from operative engagement with the sole during the movement of the jack in 75 the opposite direction.

Still further features of the invention consist in certain novel features of construction, combinations, and arrangements of parts hereinafter described and claimed, the 80 advantages of which will be obvious to those skilled in the art from the following description.

In the accompanying drawings illustrating the preferred form of the invention, 90 Figure 1 represents a partial side elevation of a machine embodying the several features of the invention in their preferred form; Fig. 2 is a detail illustrating a front elevation partly in section of a jack and the 95 co-operating channel flap laying mechanism; and Fig. 3 is a detail showing a side elevation of the mechanism illustrated in Fig. 2.

The illustrated embodiment of the invention is shown in connection with a machine 100 of the type disclosed in the U. S. Patent to Mayo, No. 845,714, dated February 26, 1907, but it is to be understood that the invention may also be embodied advantageously in other machines of this type which shape the 105 sole by a direct pressure.

The machine is provided with a shoe supporting jack 1 constructed to receive a last

or follower 2 which coöperates with a pressing form 3 to level the shoe by a direct pressure. The jack is arranged to reciprocate in horizontal guideways formed in a table 5 which is moved vertically in the machine frame 6. The jack is moved from a position of presentation to a position beneath the pressing form, and vice versa, by a lever 8 and link 9 actuated in the usual manner through mechanism not shown. After the jack has been moved to a position directly beneath the form, the latter is released and allowed to seat itself by gravity upon the shoe, in which position it is locked through a cam 10 actuated by the connecting rod 11. An upward movement is then imparted to the table to apply the pressure to the sole through a toggle joint, one member of which is indicated at 12. As this mechanism is old and well-known in the art and is fully disclosed in the patent above referred to, it has been only briefly described herein. It has been usual heretofore when leveling the sole in this manner to first jack the shoe and lay the channel flap by rubbing out the marginal portions of the sole manually. In the present invention this mode of operation has been improved by causing the channel flap laying operation to be performed mechanically by the machine after the shoe has been jacked and prior to the leveling of the sole.

In the simplest and most efficient form of the invention which has yet been devised the inward movement of the jack from a position of presentation to a position of clearance beneath the form is utilized to lay the channel flap, thus enabling this added operation to be performed without varying the mode of operation of the machine or necessitating any greater length of time than is required for performing the leveling operation alone.

In the illustrated embodiment of the invention a pair of flap laying rolls 15 are supported above the last 2 by standards 16 rigidly secured to the table 5. The two rolls are loosely journaled at their outer ends in a roll carrier 18 slidably mounted in the standards 16 and having its opposite ends operatively connected to cams 20 mounted upon the jack 1 and so arranged that as the jack is moved beneath the rolls the latter are depressed to engage with the surface of the sole. Each end of the carrier is connected to its respective cam through a lever 22 fulcrumed upon the standard at 23 and connected to the carrier at one end through a tension spring 24. The rolls are normally elevated above the level of the sole by a pair of springs 26 interposed between the ends of the carrier 18 and the standards 16.

As shown clearly in Figs. 2 and 3 of the drawings the upper end of each standard is provided with a longitudinal slot in which

the end of the carrier slides and the bottom of the slot is provided with a recess 25 in which the spring 26 is seated. With this construction, as the jack is moved beneath the rolls the levers 22 are actuated to depress the roll carrier through the springs 24 until the rolls engage with the shoe sole, the springs 26 yielding to allow this movement to take place. In order that the rolls may accommodate themselves to the varying curvature of different portions of the sole the outer end of each roll is provided with a stud 28 which is loosely received in a recess 29 formed in the carrier 18. The inner ends of the rolls are operatively connected through a spherical member 31 engaging with corresponding recesses formed in the adjacent faces of the rolls and are maintained in operative engagement with the sole by a pair of plungers 33 slidably supported in the carrier and yieldingly pressed against the rolls by springs 35. It will be evident from the above described construction that the rolls will be turned by contact with the sole as the shoe moves thereunder and in order to cause this movement to rub the margins of the sole outwardly each roll is provided with a spiral groove of suitable form as shown clearly in Fig. 2.

Although it is desirable that the marginal portions of the sole shall be rubbed outwardly prior to the leveling operation in order to cause the surface of the sole to present a smooth, unbroken appearance after it has been leveled, it is further desirable that the flap laying devices shall be removed from contact with the sole during the return movement of the jack to a position of presentation. To this end each lever 22 is provided with an inwardly extending arm 40 which is engaged by an arm 42 loosely fulcrumed upon the inside of the standard at 23. The arm and lever are so arranged that as the jack moves inwardly from a position of presentation to a position of clearance beneath the form the arm 42 engages with the arm 40 and through the latter actuates the lever to depress the roll carrier. Upon the return movement of the jack, however, the arm 42 is swung in the opposite direction and the movement of the arm through contact with the cam 20 does not effect the lever 22. In order to allow the arm 42 to swing in the opposite direction upon the return movement of the jack the cam 20 is provided with a recessed portion 45, as shown clearly in Figs. 1 and 3.

The operation of the improved mechanism is as follows:—After the shoe has been jacked the machine is started and the jack is first moved inwardly on the table from a position of presentation to a position of clearance beneath the form. During this movement the rolls are yieldingly pressed

against the sole by the cams 20 and the relative traverse of the rolls and jack causes the former to rub the margins of the sole outwardly. Owing to the manner in which they are supported the rolls are free to tip in any direction as the shoe passes thereunder to conform to the varying curvature of the sole. After the jack has reached a position of clearance the form is moved to seat it upon the sole and the table is then actuated to cause the form to press the surface of the sole. After the pressing operation is completed the jack is returned to its initial position and the cam 20 and arm 42 are so constructed and arranged that this return movement does not affect the rolls 15 which are retained in an elevated position by the springs 25, thus causing the rolls to operatively engage with the sole prior to 20 the leveling operation only.

While it is preferred to employ the specific construction and arrangement of parts shown and described, it will be understood that this construction and arrangement is not 25 essential except so far as specified in the claims, and may be changed or modified without departing from the broader features of the invention.

The invention having been described, what 30 is claimed is:

1. A machine for operating upon soles having, in combination, a shoe supporting jack, a pressing form, mechanism for moving the jack inwardly and upwardly from 35 a position of presentation to a position of pressure, a channel flap laying device, and means for actuating the device to lay the channel flap controlled by the inward movement of the jack.

2. A machine for operating upon shoe soles having, in combination, a pressing form, a shoe supporting jack, a channel flap laying roll, and mechanism for actuating the jack relative to the roll and form to first 45 lay the channel flap and next level the sole with a continuous movement of the jack.

3. A machine for operating upon shoe soles having, in combination, a pressing member, a shoe supporting member, mechanism 50 for relatively actuating the members to move them toward one another and apply a direct leveling pressure to the shoe sole, and means for rubbing the margin of the sole outwardly to lay the channel flap as the members are moved toward one another into a pressing position.

4. A machine for operating upon shoe soles having, in combination, a pressing member, a table, a jack supported upon the 55 table, mechanism for moving the table toward and from the pressing member and for sliding the jack on the table, and a device acting upon the shoe sole to rub out

and smooth the surface as the jack is moved horizontally upon the table. 65

5. A machine for operating upon shoe soles, comprising a table, a shoe supporting member slidingly mounted upon the table, a roll supported on the table above the shoe supporting member, and means 70 actuated by the movement of the shoe supporting member for causing the roll to bear upon the shoe sole as the latter moves thereunder.

6. A machine for operating upon soles 75 having, in combination, a shoe supporting member, a sole pressing member, mechanism for moving the shoe supporting member toward and from the sole pressing member, a channel flap laying device, and means for 80 causing the channel flap laying device to operatively engage with the sole when the shoe supporting member is moved in one direction and to retain the device out of engagement with the sole when the member 85 is moved in the opposite direction.

7. A machine for operating upon shoe soles, comprising a shoe supporting jack, a coöperating roll, means for causing a relative longitudinal movement of the roll and 90 jack in two directions, and means for automatically pressing the roll in engagement with the shoe sole when the jack moves in one direction and for removing the roll from contact with the sole when the jack 95 moves in the opposite direction.

8. A machine for operating upon shoe soles, comprising a table, a shoe supporting jack slidingly mounted on the table, a co-operating roll, a lever operatively connected 100 with the roll, and a cam mounted upon the table and arranged to actuate the lever and press the roll against the shoe sole as the jack is moved under the roll.

9. A machine for operating upon shoe 105 soles having, in combination, a table, a shoe supporting jack slidingly mounted on the table, a roll carrying head, and coöperating rolls journaled in the head above the jack having provision for a yielding angular 110 movement to conform to the varying curvatures of the sole.

10. A machine for operating upon shoe soles having, in combination, a table, a shoe supporting jack slidingly mounted on the 115 table, a roll supported upon the table above the jack, a lever connected with the roll, a cam movable with the jack, and means for automatically engaging the cam and lever when the jack is moved in one direction and 120 for disconnecting them when the jack is moved in the opposite direction.
